UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

MOUNTING FOR CONCRETE BREAKERS.

Application filed July 10, 1925. Serial No. 42,643.

To all whom it may concern:

Be it known that I, CHARLES C. HANSEN, a citizen of the United States, and a resident of Easton, in the county of Northampton and State of Pennsylvania, have invented a certain Mounting for Concrete Breakers, of which the following is a specification, accompanied by drawings.

This invention relates to concrete breakers, but more particularly to a mounting for fluid actuated concrete breakers of the hammer type.

One object of the invention is to mount a concrete breaker on a vehicular mounting to relieve the operator of the constant strain of supporting the tool.

Another object is to prevent the transmission of shock and vibration to the operator when the tool is in operation.

20 Further objects will appear hereinafter.

The invention consists of the combinations of elements, features of construction, and arrangement of parts having the general mode of operation substantially as hereinafter described and more particularly pointed out in the appended claims and illustrated in the accompanying drawings, in which

Figure 1 is a side view in elevation partly in section of the universal mounting for a concrete breaker;

Figure 2 is a front end view in elevation, and

Figure 3 is a top plan view of the mounting.

Referring to the drawings, the mounting comprises a pair of wheels A having an axle B to which are secured handle bars C as by means of clamps D. The handle bars C are preferably of tubular form and are provided at the rearward end with a hollow cross piece E secured to said handle bars by suitable clamps F to serve as a grip whereby the operator may manipulate the device.

In practice, it is desirable to provide the smoothest possible surface for the wheels A and also to provide the best footing obtainable for the operator. To this end the handle bars C are extended through the clamps D to provide a support for the fluid actuated percussive tool G in such a manner that the wheels A will be between the operator and the tool G.

55 In order to enable the tool G to be ad-

justed vertically to suit varying conditions, a pair of posts H are arranged slidably within bearings J clamped to the front end of the handle bars C. Any suitable means may be provided for holding the posts H against endwise movement as for instance, set screws K. In this instance, a bracket L having a pair of bearings O is arranged slidably on the posts H to provide a support for a yoke P arranged between the bearings and secured thereto by means of pivot bolts P'. In order to oppose downward movement of the bracket on the posts H, a spring Q is interposed between said bracket and a collar R carried by the posts. A similar spring S is arranged above the bracket L and is held in position by a collar T for opposing upward movement of the bracket on the posts.

A pivot U is arranged through a handle V of the tool G and extends through the yoke P for supporting the tool. Suitable means are provided for rocking the tool G through a plane paralleling the axle B for locating the working point of a cutting implement or chisel W. For this purpose, a pinion X pivoted on a shaft Y is arranged rotatably in the bracket L for actuating a rack Z held slidably on the bracket L by suitable clamps b. The bracket L carries a pair of plates e to form bearings for a rocker arm d attached to the handle V of the tool G. In order to rotate the pinion X a rod e extending to the operator's position is connected to the shaft Y by means of a universal joint f. A hand wheel g is secured to the rearward end of the rod e to provide a convenient means for manipulating said rod. A somewhat similar arrangement is provided for swinging the tool G in a plane transverse to the axle B. For this purpose, an arm h is secured to the yoke P and has an eye j at its free end to receive the end of a rod k which like the rod e, also extends to the operator's position.

Pressure fluid for actuating the percussive element of the tool G is admitted through a supply tube o which in this instance is secured to the hollow rod E. The admission of pressure fluid into the tool G through a flexible tube p is controlled by a suitable throttle valve q.

To the end that the chisel W may be prevented from sliding out of the tool G when said tool is transported from place to

place, a retaining member *r* is attached to the tool *G* to embrace the chisel *W* in advance of a collar *s* formed on said chisel. In this way, when the tool is raised, the retaining member *r* will engage the collar *s* and prevent the shank end of the chisel from being withdrawn from the tool.

In the operation of the device, the mounting, together with the percussive tool, may be wheeled to the desired position and pressure fluid may then be admitted to the tool *G* by opening the throttle valve *q*. After the chisel *W* has penetrated the work to a desired depth, the operator may either pull or push on the rod *E* and thus drive the broken material free from the mass.

If it is not convenient or desirable to shift the entire mounting for a succeeding cut along the face of the work, the rod *e* may be rotated to rock the tool *G* about the pivot *U*, depending of course, upon the direction in which it is desired to move the tool with respect to the preceding cut, and the chisel *W* may then be driven into the work as previously described. If, on the other hand, it is desired to locate the chisel *W* in advance or to the rear of the preceding cut, the operator may pull or push on the rod *k*, as the case may be, to rock the yoke *P* and consequently the tool *G* about the pivot *P'*. Pressure fluid may then be supplied for driving the chisel into the work. The rod *k* also provides a convenient means for prying the broken concrete free from the work, if for any reason it is preferable to hold the mounting in a stationary position.

I claim:

1. A concrete breaker comprising a pair of wheels, an axle for the wheels, handle bars supported by the axle, posts secured to the handle bars, a yoke mounted on said posts, a fluid actuated percussive tool secured pivotally to said yoke, and a working implement to receive the hammer blows of the tool.

2. A concrete breaker comprising a pair of wheels, an axle for the wheels, handle bars secured to the axle, upright posts secured to the handle bars, a pivoted yoke mounted slidably on said posts, a fluid actuated percussive tool secured pivotally to said yoke, and a working implement to receive the hammer blows of the tool.

3. A concrete breaker comprising a pair of wheels, an axle for the wheels, handle bars supported by the axle, a pair of upright posts secured to the handle bars, a yoke slidable on said posts, said yoke being pivoted at its ends, a fluid actuated percussive tool, a handle on said tool, said handle being pivoted on the yoke, and a working implement inserted into the tool to receive the hammer blows of said tool.

4. A concrete breaker comprising a pair

of wheels, an axle for the wheels, handle bars supported by the axle, a pair of upright posts secured to the handle bars, a yoke slidable on said posts, said yoke being pivoted at its ends, springs for opposing movement of the yoke on the posts, a fluid actuated percussive tool, a handle on said tool, said handle being secured pivotally to said yoke for supporting the tool, and a working implement extending into the tool to receive the hammer blows of the tool.

5. A concrete breaker comprising a pair of wheels, an axle for the wheels, handle bars secured to the axle, a pair of upright posts supported by the handle bars, a yoke pivoted at its ends and slidable on said posts, springs for opposing movement of the yoke on the posts, a fluid actuated percussive tool having a handle, a pin through said handle supported by the yoke to form a pivot for the tool, a working implement extending into the tool to receive the hammer blows of the tool, and means for oscillating the tool for locating the working end of the implement.

6. A concrete breaker comprising a pair of wheels, an axle for the wheels, handle bars secured to the axle, a pair of upright posts supported by the handle bars, a yoke pivoted at its ends and slidable on said posts, springs for opposing movement of the yoke on the posts, a fluid actuated percussive tool having a handle, a pin through said handle supported by the yoke to form a pivot for the tool, a working implement extending into the tool to receive the hammer blows of the tool, and means for oscillating the tool in a plane paralleling the axle for locating the working end of the implement.

7. A concrete breaker comprising a pair of wheels, an axle for the wheels, handle bars secured to the axle, a pair of upright posts supported by the handle bars, a yoke pivoted at its ends and slidable on said posts, springs for opposing movement of the yoke on the posts, a fluid actuated percussive tool having a handle, a pin through said handle supported by the yoke to form a pivot for the tool, a working implement extending into the tool to receive the hammer blows of the tool, and means for oscillating the tool in a plane transverse to the axle for locating the working end of the implement.

8. A concrete breaker comprising a pair of wheels, an axle for the wheels, handle bars secured to the axle, a pair of upright posts secured adjustably to the handle bars, a yoke slidable on the posts and pivoted at its ends, springs to oppose movement of the yoke on the posts, a fluid actuated percussive tool having a handle, a pin extended loosely through said handle supported at its ends by the yoke to provide a pivot for the tool, a working implement extending into the tool to receive the hammer blows of said

tool, means including a slidable rack and a pinion for manually oscillating the tool through one plane, and a rod associated with the yoke for oscillating the tool 5 through a transverse plane.

9. A concrete breaker comprising a pair of wheels, an axle for the wheels, handle bars secured to the axle, a pair of upright posts supported by the handle bars, a yoke 10 pivoted at its ends and slidable on said posts, springs for opposing movement of the yoke on the posts, a fluid actuated percussive tool having a handle, a pin through said handle supported by the yoke to form a pivot for the tool, a working implement extending into the tool to receive the hammer blows of the tool, and means including a slidable rack and a pinion stationary with 15 respect to the rack for manually oscillating the tool in the plane paralleling the axle, and a rod associated with the yoke for manually oscillating the tool and a plane transverse to the axle for locating the working end of the implement.

10. A concrete breaker comprising a pair

of wheels, an axle for the wheels, handle bars secured to the axle, a pair of upright posts supported by the handle bars, a yoke 25 pivoted at its ends and slidable on said posts, springs for opposing movement of the yoke on the posts, a fluid actuated percussive tool having a handle, a pin through said handle supported by the yoke to form a pivot for the tool, a working implement extending into the tool to receive the hammer blows of the tool, and means including a slidable rack and a pinion stationary with 30 respect to the rack for manually oscillating the tool in the plane paralleling the axle, and a rod associated with the yoke for manually oscillating the tool and a plane transverse to the axle for locating the working end of the implement.

In testimony whereof I have signed this specification.

CHARLES C. HANSEN.
